The ornamental design for a lap-top computer, as shown and described.

DESCRIPTION

FIG. 1 is a front elevational view of a lap-top computer showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front top and right side perspective view thereof;

FIG. 8 is a front elevational view thereof with the cover in the closed condition;

FIG. 9 is a right side elevational view thereof;

FIG. 10 is a top plan view thereof;

FIG. 11 is a front top and right side perspective view thereof;

FIG. 12 is a front top and right side perspective view thereof with the cover in the closed condition and the handle pulled out.
